UNITED STATES PATENT OFFICE.

FREDERICK W. REEVES, OF PITTSBURGH, PENNSYLVANIA.

ALTERNATING-ELECTRIC-CURRENT RECTIFIER.

1,203,266.

Specification of Letters Patent. Patented Oct. 31, 1916.

Application filed April 30, 1914. Serial No. 835,363.

To all whom it may concern:

Be it known that I, FREDERICK W. REEVES, a citizen of the United States, residing at Pittsburgh, in the county of Allegheny and

5 State of Pennsylvania, have invented a new and useful Improvement in Alternating-Electric-Current Rectifiers, of which improvement the following is a specification.

10 My invention has for its object, to provide a simple and practical current rectifier, to be rotatively driven in step or synchronism with and for changing alternate electric currents into a direct current for the operation of arc lamps, direct current motors, 15 etc., the device being so constructed and arranged as to prevent short circuiting in the alternate current circuit should the same vary in speed at any time and tend to get out of step with the current alternations.

20 With the above object in view, the invention consists in certain features of construction and arrangement, and in certain parts and combination of parts, as will be hereinafter more specifically described and set 25 forth in this specification and particularly pointed out in the appended claims.

Broadly, the invention comprises a rectifier formed of plural sets of unitary contacts, connected in circuit with and adapted 30 to be rotated to cause the contacts thereof to be in step with the current alternations, and means also connected in said circuit for engaging the contacts of said sets.

In describing the invention in detail, reference is to be had to the accompanying drawings, forming a part hereof, wherein one example, of a convenient and compact form, of my invention is shown, in which drawings like detail parts thereof are indicated by like numerals and referred to by such in the description following later, said drawings representing the following views:

Figure 1 is an end elevation of the current rectifying device, as applied in practice to means for operating the same. Fig. 2 is a side elevation of the same. Fig. 3 is a diagram illustrating the same in practice. Fig. 4 is an enlarged end elevation of the rectifier proper. Fig. 5 is a side elevation 50 of the same, in section on the line V—V of Fig. 4. Fig. 6 is a view similar to that of Fig. 4, with one head removed. Fig. 7 is a longitudinal sectional view through the con-

tact portions of the rectifier, on the line VI—VI of Fig. 6. Fig. 8 is a diagram 55 similar to that of Fig. 3, but with reversed circuit connections.

Referring to said drawings for the construction in detail of the rectifier proper, the same comprises a member or spool, for the 60 various contacts or divisions, formed of the sleeve 1 having an integral head 2 near one of its ends and a detachable like head 2' fitted over the opposite end thereof, both of said heads having spaced bolt openings 65 formed therethrough. The various contact portions of the rectifier are disposed about, but not touching, the sleeve between the heads thereof, said contacts being, in this instance, disposed about the holder in three 70 sections, there being insulation, as shown, between each section and between the outer sections and heads of the holder. One section of the contacts is divided into a plurality of contacts or segmental parts, comprising the live segments 3, 3^a, 3^b and 3^c, 75 between which are alternately disposed the shorter dead segments 4, all of which segments are insulated from one another, as shown. The other sections of the rectifier 80 are, in this instance, in the form of two rings 5 and 6, respectively, both disposed at one side of the segmental contact section, and, as before stated, insulated from one another, as shown, the ring section 5 being 85 connected to the two opposite commutator segments, 3^a and 3^b, by bars 7, and the ring sections 6 connected to the segments 3 and 3^c, by bars 8. As will be apparent, the ring 90 5 and the two segmental contacts 3^a and 3^b being connected to one another form a unitary structure or contact, as does likewise the ring 6 and the other two segmental contacts 3 and 3^c, which, in this instance, have their segmental contact portions disposed in 95 alternate relation between one another.

Bolt openings are formed through the ring contact sections and segmental parts of the divided section, registerable with those in the heads of the holder, through which openings 100 are disposed bolts 9 to which are fitted nuts 10 securing said sections to the holder, said bolts and nuts being insulated from the parts through which they pass, and from the heads, as shown. The rectifier is suitably secured to the drive shaft 11 extending

through a bearing 12 on the standard 13 of suitable driving means to drive the same in synchronism with the current alternations, as for instance, a synchronous motor.

- 5 The brush holder for the rectifier, comprises a four armed spider 14, each arm thereof being disposed at an angle of 90 degrees with respect to one another, secured in adjusted position upon an extension of 70
- 10 the bearing 12 of the driving means, by means of the insulated handle 15 threadably secured to said spider and engaging the bearing extension. To each arm of the spider is insulatedly secured a brush holder 75 proper which extends toward and over the rectifier contacts, designated as 16, 17, 18 and 19, respectively, each holder having a transverse opening in its forward end to receive the brushes and provided with a binding post 20. The brush holders 16 and 17, which are of equal length, are those intended for the brushes which operate on the segmental section of the rectifier, which in 80 this particular instance must be so disposed
- 15 that when the brushes are fitted thereto that said brushes will be disposed at an angle of 90 degrees with respect to one another. The brush holder 18 is of greater length and is intended for the brush operating on the 85 section 5 of the rectifier, and the brush holder 19, which is of still greater length, is intended for the brush operating on the section 6 of the rectifier, but, owing to the sections 5 and 6 being in this instance of ring 90 form, the brushes and holders therefor may be disposed at any point other than shown. The brushes 21, 22, 23 and 24, fitted in the 95 openings at the end of the respective holders, are each preferably formed of two carbon plates, disposed one along side of the other, there being springs 25 fixed to the holders to engage the brushes and keep the same in contact with the rectifier engaged thereby.
- 40 45 In the diagram shown in Fig. 3, the brushes 21 and 22 are shown as connected in circuit with an alternating current generator 26, by circuit wires 27 and 28, and the brushes 23 and 24 as connected to an arc lamp 29, by circuit wires 30 and 31, as one illustration of the rectifier in practice.
- 50 In the diagram shown in Fig. 8, the alternating current generator 26 is connected to the circuit wires 30 and 31 and the arc lamp 29 connected to the circuit wires 27 and 28, as another illustration of the rectifier in practice.
- 55 In both of the above diagrams, the generator 26 is shown as an example of alternating current supply, and the arc lamp 29 as an example of one of the many uses for the current when rectified into a direct current, such examples serving in this instance to describe the operation of the rectifier.
- 60 65 In practice, each of the live segments 3, 3^a,

3^b and 3^c of the rectifier, represent in breadth, practically, one alternation of current and the dead plates 4 each representing, practically, the zero period between alternations, then if the rectifier be rotated, say in 70 the direction of the large arrow, so that each live segment be in step with the current alternations the following would be an example of operation:

Referring to Fig. 3, if it be assumed that 75 the rectifier is in a position with the brush 22 on the live segment 3 and the brush 21 on the live segment 3^a, the current alternation coming from the generator 26, as long as the brushes are on said segments, will pass 80 from the generator, in the direction indicated by the small full lined arrows, by way of the wire 27, brush 22, segment 3, connection 8, ring 5, brush 23, wire 31, to and through the lamp 29, through wire 30, brush 85 24, ring 6, connector 7, segment 3^a, brush 21, and wire 28 back to the generator, and as the said rectifier advances beneath the brushes to cause the segments 3 and 3^a to pass from beneath the brushes at the 90 end of the current alternation, the said brushes will then each be on one of the dead segments 4 during the zero period between current alternations. As the rectifier further advances to bring the brushes 95 21 and 22 into engagement with the segments 3 and 3^b, in synchronism with the next alternation of current, the current will then pass from the generator 26 along the wire 28, as shown by dotted arrow, through 100 brush 21 and segment 3, then, as shown by the full lined arrows, along connector 8 and through ring 5, brush 23, wire 31, through lamp 29, wire 30, brush 24 and ring 6, then, as shown by the small dotted arrow, through 105 the connector 7, through segment 3^b and brush 22, and, as shown by dotted arrow, through wire 27 to the generator.

In the above described operation, representing two complete alternations in reverse 110 direction from the source of supply, or one cycle of current, it will be observed that, while the current passes from the generator in alternate directions, the rectifier converts the same into a direct current to supply the 115 lamp, and will continue to do so as each live segment of the rectifier contacts with the brushes, as will be apparent.

In the diagram shown in Fig. 8, the connections of the generator and lamp are reversed from that shown in Fig. 3, in which instance the current would flow from the generator at one alternation, when the brushes 21 and 22 are on the segments 3^a and 3, as indicated by the small arrows in full 120 lines, that is to say, from the generator to the lamp, by way of the wire 30, brush 24, ring 6, connector 7, segment 3^a, brush 21 and wire 28 to the lamp 29, and from the lamp 125 by way of the wire 27 and brush 22, through 130

segment 3, connector 8 and ring 5 to brush 23 and wire 31 to the generator. When the brushes 21 and 22 are on the segments 3 and 3^b, the next alternation of current passes from the generator along the wire 31 to the segment 3, as shown by dotted arrows, by way of the brush 23, ring 5 and connector 8, and from said segment 3 to the brush 21 and along wire 28, as shown by full lined arrow, 10 to the lamp, then from said lamp, by way of the wire 27 and brush 22 to the segment 3^b to the ring 6, by way of the connector 7, as shown by dotted arrow, then from said ring back to the generator, by way of the 15 brush and wire 30, as indicated by the dotted arrow.

From the two examples of operation given, it will be readily apparent that it makes no difference as to which set of 20 brushes the generator or the lamp be connected, the result of current rectifying being the same.

The dead plates 4 in the rectifier, are 25 really nothing more than inactive or insulated spaces between the active segments, but, like that of the active segments, are made of metal so as to give a uniform wearing surface about the rectifier, said segments 4, or insulated space, being preferably 30 slightly greater in width than that of the brushes so as to prevent short circuiting and arcing should the rectifier get out of step with the current alternations.

While I have shown and described my invention as of a particular form and application, it is to be understood that the said form and application are intended only to serve 35 as an example, and that in practice the arrangement, modification and details of same 40 may be made without departing from the spirit of my invention herein claimed.

What I claim as my invention and desire to secure by Letters Patent, is:

1. An alternating electric current rectifier, comprising in combination a rotative sleeve 45 having a flanged head at each end, a pair of contact rings disposed on said sleeve between the heads, each ring being provided with a plurality of spaced live contacts, the contacts of one ring being disposed between 50 and in alternate relation with the contacts of the other ring, dead contacts disposed between said live contacts, means extending through the sleeve heads and each of said live and dead contacts to secure the structure 55 together, and two sets of brushes, one set operating on the rings and the other set on the contacts.

2. An alternating electric current rectifier, comprising in combination a rotative 60 sleeve having a flanged head at each end, one of which is detachable, a pair of contact rings disposed on said sleeve between the heads, a plurality of spaced live contacts 65 also arranged on said sleeve, one half the number of said live contacts being connected to one of said rings and the other half number connected to the other ring, dead contacts disposed between said live 70 contacts, means extending through the sleeve heads and each of said live and dead contacts to secure the structure together, and two sets of brushes, one set operating 75 on said rings and the other set on said contacts.

In testimony whereof, I have hereunto signed my name in the presence of two subscribing witnesses.

FREDERICK W. REEVES.

In the presence of—

R. S. HARRISON,
EMMA M. HALL.
